UNITED STATES PATENT OFFICE.

RICHARD P. WEAVER, OF CARLISLE, PENNSYLVANIA.

SECTIONAL RAILWAY-CROSSING.

1,391,227.

Specification of Letters Patent. Patented Sept. 20, 1921.

Application filed February 2, 1921. Serial No. 441,914.

To all whom it may concern:

Be it known that I, RICHARD P. WEAVER, a citizen of the United States, residing at Carlisle, in the county of Cumberland and 5 State of Pennsylvania, have invented certain new and useful Improvements in Sectional Railway-Crossings, of which the following is a specification, reference being had to the accompanying drawings.

10 This invention relates to railway crossings, and particularly to railway crossings where the crossing is formed of a plurality of sections of structural material bolted together to form the crossing.

15 The general object of my invention is to provide a crossing made up of a plurality of sections, and provide means whereby the crossing sections may be interlocked with each other by means of wedges which will 20 act to force the sections into interlocking engagement.

And a further object is to provide a crossing which will not crack or break at intersection of flangeways.

25 Another object is to provide a crossing which may be readily made of manganese or alloy steel.

Other objects will appear in the course of the following description.

30 My invention is illustrated in the accompanying drawings, wherein:—

Figure 1 is a perspective view of a railway crossing constructed in accordance with my invention;

35 Fig. 2 is a section on the line 2—2 of Fig. 1;

Fig. 3 is a fragmentary perspective view of two of the main sections and one of the corner sections and the wedge for locking 40 the sections together;

Fig. 4 is a section on the line 4—4 of Fig. 1;

Fig. 5 is a section on the line 5—5 of Fig. 1;

45 Fig. 6 is a section on the same lines as Fig. 4, but showing the parts separated;

Fig. 7 is a horizontal sectional view of the vertex of one of the sections B and the tongue 37.

50 Referring to these drawings, and particularly to Figs. 1 and 3, it will be seen that my crossing is formed essentially of eight sections, namely four main sections A, A', A² and A³ and four corner sections B, B', B² and B³. These main sections are all alike 55 and the corner sections are all alike. Hence

a description of one of the main sections will apply to all and a description of one of the corner sections will apply to all.

The main section A³, for instance, is approximately U-shaped in form, that is it is provided with a portion 10 and angularly disposed arms 11, as they may be called. The part 10 of the main section is approximately U-shaped in cross section so as to 60 provide a tread portion having a longitudinal groove 12 and provide the downwardly extending webs 13, each formed with an outwardly extending flange 14, as shown most clearly in Fig. 3. The groove 12 extends the 65 entire length of the portion 10 and is designed to receive the flange of the wheel, while outward of this groove there is a bearing face 15 to receive the tread of the wheel. Each of the arms 11, as illustrated in section 70 in Fig. 6, is formed to provide a vertical web 16 having an outwardly extending base flange 17, but the inner face of this arm for a portion of its length has its longitudinally 75 extending head 18 recessed on one edge face, 80 as at 19, to form one wall of a flange groove and below this part 19 with a longitudinally extending recess 20 extending parallel to the base of the arm. The lower wall 21 of this 85 recess 20 or groove extends out beyond the inner face of the head 18 and the under face of this flange 21 so formed is formed to provide a downwardly projecting longitudinally extending tongue 22, this tongue being 90 beveled in opposite directions upon its under face so that between the apex of this tongue and the web 16 a relatively deep recess 23 is formed. This is shown most clearly in Fig. 6. The head 18 extends along the arm 11 for a portion of its length and then the 95 head is cut away but the web 16 is continued for a certain distance. This continuation of the web 16 is perforated at a plurality of points, as at 24, for the passage of bolts whereby a rail may be held in place, as will 100 be later stated.

Coacting with these members A, A', A² and A³ at each corner of the crossing are the corner members B, B', B² and B³ heretofore referred to. Each corner member is 105 constructed as illustrated in Fig. 3 and is right angular in plan view. The body of each corner member is longitudinally grooved, as at 25, this groove extending vertically from the lower face of the section. 110 Each corner member upon its outer reentrant face is formed with a base flange 26,

the base flanges of the members B, B', B² and B³ and the base flanges of the members A, A', A² and A³ being for the purpose of permitting the sections to be attached to ties or any other substructure by means of spikes in the usual manner and secure a full bearing surface for the under side of the section. The inner face of each of the corner sections, that is that face confronting the two arms 11 of adjacent main sections, is formed to provide an inwardly projecting flange 27 below the upper or tread face of the corner section, the upper face of this flange being connected to the tread face of the corner section by an ogee curve, as at 28. This flange is designed to engage in the recess 20 but is less in thickness than the depth of this recess. Below the flange 27 there is a base flange 29 which is adapted to rest upon the ballast or substructure, and the upper face of this flange extends downward and outward from the vertical web 30 of the corner section, as at 31, then upward and outward. In other words, the upper face of this flange 29 fits against and interlocks with the under face of the flange 21, the upper face of the flange 29 being formed with what amounts to a longitudinally extending groove which receives and interlocks with the longitudinally extending tongue 22 on the flange 21. The flange 21 is less in thickness than the space between the flange 27 and the upper face of the flange 29 so that a space is left between the confronting faces of the two flanges when these two sections are in engagement with each other, and into this space a locking wedge 32 is designed to be forced, this locking wedge forcing the tongue 22 of flange 21 into engagement with the recess or groove in the upper face of the flange 29, as most clearly shown in Fig. 4. This wedge 32 is formed upon its upper face with a longitudinally extending groove 33.

It will be seen from Fig. 4 that when the corner section is disposed in engagement with one of the main sections, the face 19 of the head 18 of the main section and the face 28 of the corner section will together form a flange groove 12^a which will form a continuation of one of the flange grooves 12. Each of the arms of the corner sections is likewise reduced in width by removing the tread face or head of the corner section so as to leave a portion 34 constituting practically a fish plate which will engage with the usual guard rail C and main rail D separated by a filler E. Thus the arm 11 of one main section will confront the arm of one corner section and the railroad rails be gripped between these two arms, the confronting faces and the vertical webs of these arms being formed, as at 35, to engage between the base and head of the said railway rails. These portions of the corner section

are perforated, as at 36, for the passage of bolts which pass through the apertures 36, through the railway rail, and through the apertures 17 in the arms of the main section.

Each of the corner sections has projecting from its vertex, that is the junction of its two arms, a lug 37, this lug being formed with a head 38 at its extremities, the side faces of this head being flared so that the head is approximately triangular in plan view, these angular faces of the head fitting closely against the reentrant angle formed by the conjunction of two adjacent main sections. Where this lug 37 crosses the flange 27, it is reduced in thickness, as at 39, to form a continuation of the grooves 12^a which extend across it at right angles and which intersects at this point. Preferably the head 38 is formed on its side face with drift grooves 40. (See Fig. 7.)

It will be seen that with this construction the main sections of the crossing are disposed to define a square and that then the corner sections are placed at the corners of the square and the arms 11 of the main sections are engaged with the legs of the corner sections by disposing the flanges 21 of the main sections between the flanges 27 and 29 of the corner section and locking the parts in this position by the insertion of the wedges 32. Thus it will be seen that the section A³ is held to the sections B and B³ by wedges extending parallel to the arms 11 of the main section A³, that the section A is held to the sections B and B' by wedges, that the section A is held to the section B' and B² by like wedges, and that the section A is held to the section A² and B³ by wedges. There are thus eight wedges used to hold the four main sections A, A', A² and A³ to the four corner sections B, B', B² and B³. Thus a section taken transversely of each arm 11 and through the arm of the corresponding corner section would show a construction such as that illustrated in Fig. 4. Thus each section of the crossing is interlocked with the two adjacent sections by these wedges 32. Once the wedges are inserted and driven home, the eight sections of the crossing will be interlocked with each other very strongly and the crossing can be handled as if it was only one integral piece or casting or as if it was made of separate sections welded or brazed to each other or bolted to each other.

A crossing of this character will not crack or break under service usage, and at the same time it is entirely possible to withdraw any of the sections and replace a worn section by a new section by simply removing the wedges 32 connecting a corner section or sections with the adjacent main sections.

It will be seen from Fig. 7 that the drift

grooves 40 intersect at an opening 37^a which passes through the lug 37 so that wedges 32 may be driven out by using a drift bar inserted along the grooves 40, as shown in dotted lines in Fig. 7, which will strike the end of the wedge and loosen it. These wedges are to be made of steel or cast steel and, being slightly tapered, they may be forced into position near the guard point 37 of the frog 10 where the wheels pass over the intersecting flangeways 12 and 12^a. The wedges are grooved, as at 33, to make grinding and fitting easy, and furthermore if the wedge was solid it would tend to crack the manganese steel flange 27 forming the bottom of the flangeway 12^a. The wedges should fit tightly, but not so tightly that they cannot be released. As will be seen from Fig. 3, the flanges 27 are each about 1" wider at their 15 junction with the lug 37 than they are at their outer ends. This allows the drift bar to knock out the wedge more easily than it otherwise would do.

Crossings are either composite crossings 25 made up of rails or a manganese insert crossing made up of a number of pieces bolted together. Such a crossing gives slightly under the weight of the train when the wheels pass over the intersecting flangeways. Solid crossings do not give in this 30 manner and the pounding of the wheels going over the flangeway of a solid crossing causes it to become cracked or broken across the bottom of the flangeway. My improved 35 crossing is designed to give and yield to the motion of a train in the same manner as any all rail crossing or a manganese insert crossing and yet at the same time permit the parts to be cast. It will be noted that the 40 flange 27 which forms the bottom of the intersecting flangeways 12^a is supported by the wedge 32, which in turn is supported by the flange 21, and this in turn is supported by the base flange 29 so that beneath the 45 intersections of the flangeways 12 and 12^a, the material forming the bottom of the flangeway is fully supported against downward pressure and cracking strains. If one of the cast sections becomes broken or defective in 50 molding, it is not necessary to throw away more than $\frac{1}{3}$ of the crossing, whereas in a solid cast crossing from $\frac{1}{4}$ to $\frac{1}{2}$ of the crossing is thrown away, as they are made in two and four pieces. One of the main 55 objects of my crossing is to form a crossing of cast sections but in which braces and bolts to hold the crossing sections together shall be eliminated.

I claim:—

60 1. A railway crossing formed of a plurality of sections, each section having interlocking engagement with the next adjacent sections, and wedges holding the sections in interlocked engagement.

65 2. A railway crossing formed of a plu-

rality of sections, the confronting faces of any two sections being formed one with a longitudinally extending recess and the other with a longitudinally extending flange 70 engaging in said recess, one wall of said recess and the confronting face of the flange being formed with a coacting tongue and groove, and a wedge disposed between one face of the flange and the confronting wall 75 of said recess to urge the tongue and groove into interlocking engagement with each other.

3. A railway crossing of the character described formed of a plurality of main sections, each main section having a body portion and arms at opposite ends extending at right angles to the body portion, said main sections being arranged in quadrilateral relation to each other, corner sections 80 each having arms disposed at right angles to each other, the corner sections being disposed at the exterior angles of the intersection of the arms of the main sections, and means for interlocking the main sections with the corner sections. 90

4. A railway crossing of the character described formed of a plurality of main sections, each main section having a body portion and arms at opposite ends extending at right angles to the body portion, said main sections being arranged in quadrilateral relation to each other, corner sections each having arms disposed at right angles to each other, the corner sections being disposed at the exterior angles of the 95 intersection of the arms of the main sections, said corner sections and the confronting faces of the main sections being formed to provide longitudinally extending interlocking flanges and recesses, and means for holding 100 said flanges and recesses in interlocking engagement with each other. 105

5. A railway crossing of the character described formed of a plurality of main sections, each main section having a body portion and arms at opposite ends extending at right angles to the body portion, said main sections being arranged in quadrilateral relation to each other, corner sections each having arms disposed at right angles to each other, the corner sections being disposed at the exterior angles of the 110 intersection of the arms of the main sections, said corner sections and the confronting faces of the main sections being formed to provide longitudinally extending interlocking flanges and recesses, and wedges for holding 115 said flanges and recesses in interlocking engagement with each other, said wedges extending longitudinally along said recess. 120

6. A structure of the character set forth comprising two sections, each of said sections having portions extending parallel to each other, one of said portions being formed with an upper and a lower later- 130

ally projecting flange defining longitudinally extending recesses between the flanges, the other section having a longitudinally extending flange of less thickness than the 5 depth of the recess and insertible into said recess, the last named flange and one of the first named flanges being formed to provide an interlocking tongue and groove, and a longitudinally extending wedge disposed 10 in said recess and engaging the last named flange to force it in interlocking engagement with the coacting flange of the other section.

7. A structure of the character set forth 15 comprising two sections, each of said sections having portions extending parallel to each other, one of said portions being formed with an upper and a lower laterally projecting flange defining longitudinally 20 extending recesses between the flanges, the other section having a longitudinally extending flange of less thickness than the depth of the recess and insertible into said recess, the last named flange and one of the 25 first named flanges being formed to provide an interlocking tongue and groove, and a longitudinally extending wedge disposed in said recess and engaging the last named flange to force it in interlocking engagement 30 with the coacting flange of the other section, said members above said flanges being formed to provide each one-half of a flange groove.

8. A railway crossing composed of four 35 main sections disposed in quadrilateral relation to each other, each main section being U-shaped in plan to provide arms extending at right angles to the body of the main section, four corner sections right angular in plan to provide angularly extending 40 arms disposed in parallel relation to the arms of the main sections, and means detachably interlocking said arms with each other, each arm of each main section and 45 each arm of each corner section being reduced in thickness adjacent its outer ends to receive between them a railway rail, these reduced portions being perforated for the passage of bolts to engage the rail.

50 9. A railway crossing composed of four main sections disposed in quadrilateral relation to each other, each main section being U-shaped in plan to provide arms extending at right angles to the body of the 55 main section, four corner sections right angular in plan to provide angularly extending arms disposed in parallel relation to the arms of the main sections, and means detachably interlocking said arms with each 60 other, each arm of each main section and each arm of each corner section being reduced in thickness adjacent its outer ends to receive between them a railway rail, these reduced portions being perforated for the 65 passage of bolts to engage the rail, the tread

face of the body portion of each main section having a longitudinally extending flange receiving groove, the tread faces of the arms of the main sections and corner sections being formed to define a longitudinally extending flange receiving groove at the point of contact of said arms, these last named grooves alining with the first named grooves, each of the corner sections having lugs extending from the junction of its arms 70 and diagonal to each other, said lugs having beveled heads engaging against the inner faces of the main sections at the junctions of said main sections, said lugs being reduced in thickness at the intersection of 80 said grooves of the main sections, and means for engaging the main sections with the corner sections.

10. A railway crossing composed of four main sections disposed in quadrilateral relation to each other, each main section being U-shaped in plan to provide arms extending at right angles to the body of the main section, four corner sections right angular in plan to provide angularly extending arms disposed in parallel relation to the arms of the main sections, means detachably interlocking said arms with each other, each arm of each main section and each arm of each corner section being reduced in thickness adjacent its outer ends to receive between them a railway rail, these reduced portions being perforated for the passage of bolts to engage the rail, the tread face of the body portion of each main section having a longitudinally extending flange receiving groove, the tread faces of the arms of the main sections and corner sections being formed to define a longitudinally extending flange receiving groove at the point of contact of said arms, these last named grooves alining with the first named grooves, each of the corner sections having lugs extending from the junction of its arms 85 and diagonal to each other, said lugs having beveled heads engaging against the inner faces of the main sections at the junctions of said main sections, said lugs being reduced in thickness at the intersection of 90 said grooves of the main sections, and means for engaging the main sections with the corner sections.

11. A railway crossing composed of four main sections disposed in quadrilateral relation to each other, each main section being U-shaped in plan to provide arms extending at right angles to the body of the main section, four corner sections right angular in plan to provide angularly extending arms disposed in parallel relation to the arms of the main sections, means detachably interlocking said arms with each other, each arm of each main section and each arm of each corner section being reduced in thickness adjacent its outer ends to receive be- 110

tween them a railway rail, these reduced portions being perforated for the passage of bolts to engage the rail, the tread face of the body portion of each main section having a 5 longitudinally extending flange receiving groove, the tread faces of the arms of the main sections and corner sections being formed to define a longitudinally extending flange receiving groove at the point of contact of said arms, these last named grooves alining with the first named grooves, each 10 of the corner sections having lugs extending from the junction of its arms and diagonal to each other, said lugs having beveled

heads engaging against the inner faces of 15 the main sections at the junctions of said main sections, said lugs being reduced in thickness at the intersection of said grooves of the main sections, and means for detachably interlocking the main sections with 20 the corner sections including interlocking flanges on the confronting faces of the main and corner sections, and longitudinally extending wedges holding said flanges in interlocked engagement.

In testimony whereof I hereunto affix my signature.

RICHARD P. WEAVER.
